UNITED STATES PATENT OFFICE.

THOMAS H. BOYD, OF PAWHUSKA, OKLAHOMA.

AUTOMATIC GAS CUT-OFF.

Application filed September 25, 1924. Serial No. 739,909.

To all whom it may concern:

Be it known that I, THOMAS H. BOYD, a citizen of the United States, residing at Pawhuska, in the county of Osage and State of Oklahoma, have invented certain new and useful Improvements in Automatic Gas Cut-Offs, of which the following is a specification.

The present invention appertains to improvements in that type of safety appliances generally known as automatic cut-offs designed for automatically cutting off the flow of gas when the pressure in the supply line falls below a predetermined limit or is temporarily interrupted, and which remains closed upon an increase or renewal of the pressure.

It is quite generally known that the pressure supply of gas for heating or illuminating purposes, whether natural or artificial, is subject to fluctuation from time to time, very frequently resulting in discontinuance of the operation of the burners and when the pressure supply becomes normal again the gas is allowed to escape. Each year many lives are lost from asphyxiation and serious damage to lives and property is occasioned by explosions which are due to this uncertainty of operation of the gaseous flow. In the ordinary household small children very often turn on the gas jets of a gas stove which goes unnoticed until a large amount has escaped. In such instances unless the precautions are taken to clear the gas filled rooms, grave likelihood of injury from explosion or suffocation is encountered.

Many devices have been proposed heretofore for the purpose of elimination of the dangers aforesaid. In the majority of instances, however, the devices are expensive, complicated in structure, and therefore liable to get out of order, difficult to install and otherwise objectionable, and it has been my aim to devise under these conditions a simple, unitary device, capable of being manufactured cheaply, yet very efficient in action.

One of the primary objects of my invention is to provide such a device as will prevent the resumption of the flow of gas to the burners until manual releasing operation is resorted to, and I have had in mind the utilization of such means to this end as will permit of ready release of the cut-off by one acquainted with the manner of operation, yet not so easy as likely to be effected

by children who may be tempted to tamper with the device.

The invention is characterized as to novelty by the provision of a double unbalanced valve, so-called, which is so arranged as to be maintained in open position by the normal ranges of gas pressure acting in one direction but when closed is held so by the renewal pressure following a drop thereof, acting in the opposite direction; and further by the provision of a manually operable relief valve which causes an unbalancing of the opposing pressures, functioning to again open the valve.

Other objects and advantages of the invention will be hereinafter set forth and the novel features thereof defined by the appended claims.

In the drawing:

Figure 1 is a perspective view of an ordinary gas stove having my safety appliance in position thereon;

Figure 2 is a vertical sectional view through the automatic cut-off device;

Figure 3 is a horizontal sectional view taken about on the plane indicated by the line 3-3 of Figure 2;

Figure 4 is a sectional view of the retainer cap forming a part of the relief valve for the cut-off device;

Figure 5 is a sectional view of the nipple or body portion of the relief valve;

Figure 6 is a detail view of the relief valve and jam nut;

Figure 7 is a detail view of the spring for the relief valve shown in Figure 6; and

Figure 8 is a modified form of valve member which may be used in connection with this appliance.

Like reference characters designate corresponding parts throughout the several views.

Referring to the drawing and specifically describing the invention, 1 designates the casing of the valve device which is provided at its lower end with a closure 2 having a threaded neck 3 with which the gas supply conduit 4 is adapted to be connected. At the top the casing 1 is provided with a removable cap 5 which has threaded connection 105 with the casing and which is formed with a wrench hold boss 6 having a bushing 7 which extends through the cap and depends into the interior of the casing a suitable distance, as indicated at 8, to form a guide, the 110

function of which will be more apparent as this description proceeds.

Interiorly the casing 1 is formed with spaced partitions 9, 9' which divide the casing into the entrance chamber *a*, the main or intermediate chamber *b* and the upper or pressure control chamber *c*. Each of the partitions is formed with a central port 10, 10', that in the upper partition 9' being larger in operative area than the port of the lower partition 9. A self closing valve member 11 is mounted within the chamber and is provided with spaced valves 12 and 13 which correspond and coact with the respective ports 10 and 10' just referred to. The valve member 11 has an extension stem at its lower end, designated 14, which coacts with an apertured guide or bridge 15 formed across the inlet of the casing 1. The valve member is further provided with an upper extension 16 which coacts with the projecting portion of the bushing 7 so as to guide the valve member 11 in its operation as hereinafter set forth.

25 A by-pass 17 at one side of the valve casing establishes communication between the entrance chamber *a* and the pressure control chamber *c*, this passage preferably having inserted in the upper end thereof a plug 18 which is flattened at one side as indicated at 18', see Figure 3, for the purpose of constricting the passage to the desired extent. This is the simplest method of forming the passage having sufficient capacity for supplying pressure to the pressure chamber where pressure in the main pressure line is likely to vary in different localities. The plug 18 may of course be flattened to a greater or less extent and in this way the operative area of this by-pass may be simply regulated.

It will be noted that the central or primary chamber *b* of the casing is provided with the outlet port 19 with which is connected the service line for the appliance with which the device is designed to co-operate.

Passing now to the description of the means for relieving pressure which is built up in the chamber *c*, I provide a special relief valve which is attached to the valve casting in the bore of the bushing 7. This valve device comprises the nipple 20 threaded at its lower end as indicated at 20' and formed intermediate its length with the hexagonal wrench hold 22. The upper portion of this nipple or body is provided with a series of openings 23 which will place the chamber *c* in communication with atmosphere when the valve of the relief device is open. The lower end of the nipple is formed with a ground valve seat 24 with which the depressible valve 25 coacts in the operation of the device.

65 The upper end of the valve stem 26 for

the valve 25 is threaded to receive the correspondingly threaded cap 27 and a jam nut 29 therefor. A spring 28 is mounted in the bore of the nipple 20 and the lower end of said spring is engaged in the opening 31. 70 At its upper end the spring coacts with the face of a lug 32 of the cap 27. An important feature of this arrangement lies in the manner in which the spring 28 coacts with the nipple 20 and the cap 27 which requires 75 that the cap 27 be rotated in order to effect an unseating of the valve 25. In carrying out this phase of the construction the upper end of the nipple is cut out so as to form a cam surface 30 terminating in the shoulder 80 30'.

The lug 32 of the cap 27 is designed to ride upon the cam surface 30 and to coact with the shoulder 30' in one of the limits of its movement and also with the shoulder 30" in 85 the other of its limits of movement. The shoulder 32 of the cap 27 is maintained at the upper extremity of the cam and hence the valve stem cannot be depressed to unseat the valve until the cap 27 is rotated and the 90 lug or projection 32 rides downwardly of the cam surface 30. As soon as the cap member is released, the spring which has been placed under tension by the operation aforesaid rotates the cap in the opposite direction and incident thereto raises the valve to its closed position. This arrangement is designed to prevent too easy an operation of the valve member such as would be present in a construction requiring merely the 100 depression of the valve without a rotative movement. Accidental operation of the valve is thus eliminated to a great extent although the valve is very easily actuated by one knowing the method of its operation. 105

As a matter of convenience in manufacture, I have illustrated a modified form of valve member, depicted in Figure 8, wherein a passage is bored centrally entirely through the valve member as indicated at 110 34. This passage eliminates the necessity of the by-pass 17 and instead of using the latter by-pass the valve passage may be employed with equal effectiveness.

In operation, assuming that the device is 115 incorporated in the pressure line leading to a stove as depicted in Figure 1, the burner valve is opened and the relief valve 25 is depressed, which immediately opens the pressure chamber *c* to atmosphere allowing 120 the pressure which has accumulated in this chamber through the supply of gas passing by the by-pass 17 thereto to escape, the gas from the chamber passing out through the 125 openings 23 in the nipple. This relieves the pressure from the upper valve 13 and the pressure in the entrance chamber *a* immediately acts upon the valve 12 to elevate the valve member, whereupon the gas will pass 130 through the chamber *b* and out the outlet 130

19 to the burner. The valve member 11 is actually suspended by the flowing gas pressure which continues and is held in this position because the pressure is equalized on the opposite side of the upper valve 13 which is simultaneously opened with the valve 12. When the valve is in this position the burners are in use and as soon as these are closed the reduction of the flow through the valve chamber permits the valve to automatically close. This prevents any accidental escape of gas by opening a burner without lighting the same and in the subsequent use of the stove the burner is opened and the relief valve actuated to secure a supply of gas. While the invention is specifically applied as a safety device for a burner, still it also acts as a cut off for the main supply in the event that the pressure thereof fails so that there is not sufficient to supply the burner.

Should it happen that during the operation of the gas supply the pressure in the pressure line falls below a predetermined limit, the valve member 11 would gravitate to its seated position, closing the inlet and shutting off automatically the supply line to the stove. When the pressure subsequently rises or increases, the gas passes through the by-pass 17 into the pressure control chamber *c* where it acts upon the upper valve 13 and by virtue of the greater operative area of this valve this gas pressure holds the valve member 11 in its seated position. No gas can therefore pass through the safety appliance under the conditions until the built up pressure in the chamber *c* is relieved. To relieve such pressure and again render the gas supply to the burner operative it is only necessary as before described to slightly rotate the cap 27 of the relief valve and depress the valve 25 which allows the escape of the gas from the chamber *c* to atmosphere. Immediately an unbalanced condition is created and the pressure upwardly on the lower valve 12 effects an unseating of the valve member and the supply of gas is again operative.

It will be apparent from the foregoing that a simple arrangement is thus provided without catches and other minor structural parts which would be likely to become disordered in use and render the appliance ineffective for safety purposes. It should be understood, however, that slight changes may be made in the details of construction and arrangement of the parts without departing from the spirit of the invention and within the scope of the claims appended hereto.

Having thus described my invention, what I claim as new and desire to secure by Letters Patent is:—

1. An automatic gas cut-off of the class described comprising a casing having a gas

inlet and outlet, a chamber between said inlet and outlet, a self closing valve member freely movable mounted in said chamber controlling the inlet and adapted to be unseated by the gas pressure acting thereagainst in one direction and supported by the flow of gas therethrough, and means whereby the pressure is caused to be exerted against the valve member in the opposite direction to hold the valve member closed upon resumption of the gas pressure.

2. An automatic gas cut-off of the class described comprising a casing having an inlet and an outlet, a primary chamber between the inlet and outlet and a secondary chamber communicating therewith, each having a gas port, a valve member having a valve for each port, said member being freely openable and held open by the flowing gas pressure passing into and through said primary chamber and adapted to assume closed position upon the cessation of flow, and means for constantly by-passing said gas pressure to the secondary chamber when the valve is closed to build up a pressure in the latter for holding the valve member in such closed position.

3. An automatic gas cut-off of the class described comprising a casing having an inlet and an outlet, a primary chamber between the inlet and outlet and a secondary chamber communicating therewith, each having a gas port, a gravity valve member having a valve for each port, said member being freely openable and held open by the flowing gas pressure passing into and through said primary chamber and adapted to assume closed position upon the cessation of flow, means for constantly by-passing said gas pressure to the secondary chamber when the valve is closed to build up a pressure in the latter for holding the valve member in such closed position, and means for releasing the pressure in the secondary chamber to thereby render the valve member operable.

4. An automatic gas cut-off of the class described comprising a casing having an inlet and an outlet, a primary chamber intermediate the inlet and outlet and a secondary chamber communicating therewith, said chambers having gas ports of different operative areas, a freely movable valve member having disk valves of different diameter for the respective ports and adapted to be unseated by the gas flow entering the casing and to seat by gravity, and a by-pass constantly communicating with the secondary chamber to establish a balanced pressure upon the opposite faces of the upper valve member when open.

5. An automatic gas cut-off of the class described comprising a casing having an inlet and an outlet, a primary chamber between the inlet and outlet and a secondary

- chamber communicating therewith, said chambers having gas ports of different operative areas, freely movable valve member having a disk valve for each port adapted to be unseated by the gas pressure entering the casing, and to close by gravity alone when the pressure drops below a predetermined limit, a by-pass constantly communicating with the secondary chamber into which 10 chamber gas is supplied upon resumption of the flow whereby to create an overbalanced pressure operable upon the valve of greater area to maintain the valve member in closed position, a closure for the secondary chamber having means to guide said valve, and a manual relief valve upon the closure for said secondary chamber for releasing said overbalancing pressure.
6. An automatic gas cut-off of the class 20 described comprising a casing having an inlet and an outlet, spaced partitions dividing the casing into upper and lower chambers, a port of different area in each partition, a valve member movable free of tension and 25 having spaced valves of different operative areas for said ports, a by-pass in constant communication with the upper chamber to normally support the valve member by a flowing pressure when open and also establish 30 a holding pressure thereon when closed incident to the reduction of flowing pressure, and means for releasing the pressure in said upper chamber whereby to render the valve operative.
7. An automatic cut-off of the class de- 35 scribed comprising a casing, a main chamber through which the gas is passed to service, an inlet port therefor, a pressure control chamber, a port establishing communication 40 between said chambers, said port being of larger area than the inlet port aforesaid, a double valve member having disk valves co-acting with the said ports, means establish- 45 ing communication between the upper face of the valve within the pressure control chamber and the pressure supply, and manually operable means for at will releasing the pressure in said last named chamber.
8. An automatic gas cut-off of the class 50 described comprising a casing provided with a seat, a pressure control chamber in said casing having a valve seat of greater area, a self closing valve mounted in said casing and comprising spaced disks of different

diameters connected by a reduced stem to 55 constantly expose the opposite faces of the disks, and a release valve for said pressure control chamber including a passage leading to atmosphere and a depressible valve controlling said passage.

9. An automatic gas cut-off of the class described comprising a casing, a pressure control chamber in said casing, a self closing valve mounted in said casing, an inlet chamber communicating with the control 65 chamber through a by-pass port, and a plug for said port having a channel for the passage of gas therethrough.

10. An automatic gas cut-off of the class described comprising a casing, a pressure 70 control chamber in said casing, a self closing valve mounted in said casing, and a release valve for said pressure control chamber including a passage leading to atmosphere and a valve for said passage including a stem 75 projecting from the casing and actuating means for imparting rotation to said stem to permit of depressing the same.

11. An automatic gas cut-off of the class described comprising a casing, a pressure 80 control chamber in said casing, a self closing valve mounted in said casing, and a release valve for said pressure controlling chamber comprising a nipple having a valve 85 seat at the lower end thereof, a valve coacting with said seat having a stem projecting through the nipple, a cap connected to said stem and means for preventing movement unseating the valve until said cap member is 90 rotated.

12. An automatic gas cut-off of the class described comprising a casing, a pressure control chamber in said casing, a self closing valve mounted in said casing, a release valve for said pressure controlling chamber 95 comprising a nipple having a valve seat at the lower end thereof, a valve coacting with said seat having a stem projecting through the nipple, a cap connected to said stem, means for preventing movement unseating 100 the valve until said cap member is rotated, and a spring for holding the valve seated and coacting with the cap to restore the valve member to seated position after rotation thereof in the unseating action.

In testimony whereof I affix my signature.

THOMAS H. BOYD.
